UNITED STATES PATENT OFFICE.

WILLIAM J. COOK, OF DENVER, COLORADO, ASSIGNOR TO THE COOK RAILWAY SIGNAL COMPANY, OF DENVER, COLORADO, A CORPORATION OF COLORADO.

RAILWAY SIGNALING APPARATUS.

1,014,208.

Specification of Letters Patent.

Patented Jan. 9, 1912.

Application filed September 7, 1909. Serial No. 516,485.

To all whom it may concern:

Be it known that I, WILLIAM J. COOK, a citizen of the United States, residing in the city and county of Denver and State of Colorado, have invented certain new and useful Improvements in Railway Signaling Apparatus; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in railway-signaling apparatus of the general class set forth in my previous application, Serial Number 509,446, filed July 24th, 1909. In the construction disclosed in both of these applications, provision is made for automatically displaying signals in front of a train as the latter proceeds, the signals being displayed at any predetermined distance in advance of the train. Provision is also made for changing these signals at a predetermined distance in the rear of the train. In this way trains are notified both following and approaching another train, thus preventing either front or rear end collisions between trains upon the same track.

In my previous application, the specific apparatus relates to the use of electric lights as signals, the red lights designating danger and the blue lights the absence of danger, or a clear track. In my present application, provision is made for the use of semaphores as signals and while the apparatus as specifically illustrated, does not include the use of lights as signals, it is evident that they may be employed in conjunction with the semaphore signals.

In my present application, solenoids are employed at each station for operating the semaphore or raising it to the safe position. The solenoids, however, are only instantaneously energized, or while the car or train is passing the track make-and-break device at the station. An electro-magnet is used for locking the semaphore arm in the safe position, the same being constantly energized, while the semaphore arm is in the safe position. This, however, requires but

a small amount of current, since it is only necessary to retain a small armature bar in contact with the magnet, the latter acting upon a relatively long lever arm as compared with the short arm engaged by the core of the solenoid, and the pull on its core in order to support the semaphore arm is but little comparatively, since the said arm occupies a nearly balanced position.

Having briefly outlined my improved construction, I will proceed to describe the same in detail, reference being made to the accompanying drawing, in which is illustrated an embodiment thereof.

In this drawing: Figures 1 and 2 illustrate the apparatus employed at a single station and located on opposite sides of the track. Two sheets are employed for this purpose, because of the lack of room on a single sheet, in order to show the apparatus on a suitable scale. Fig. 3 is a diagrammatic view illustrating the apparatus employed at a number of stations, each translating device being represented by a symbol, comprising a letter surrounded by a circle, the translating devices on one side of the track being designated by the letter alone within the circle, while on the opposite side, the letter is given an exponent, ordinarily termed "prime."

The same reference characters indicate the same parts in all the views.

In further explanation of the views, it should be stated that the apparatus disclosed in Figs. 1 and 2, is shown in the position which it occupies after a train has passed the track make-and-break device at the station, and for this reason it may be assumed that the dotted wheel and axle structure, which is designated 5, in Fig. 3, designates the train which has just passed the make-and-break devices which are designated in their entirety by the reference characters 7 and 7^A respectively, the said device being located adjacent the rails of the track, which are designated by the number 6.

Before describing the mechanism further in detail, it will be explained that the various sets of apparatus located at five stations, are designated by the Roman characters I, II, III, IV, V, VI; respectively designating the apparatus at one station and on opposite sides of the track, while the characters III, IV; V, VI;

VII, VIII; IX and X; designate respectively the apparatus at the four stations immediately succeeding the station I, II.

Arranged close to each track rail 6, at 5 each station (see the Figs. 1 and 2) is a make-and-break device which, for convenience, are respectively designated by the reference character 7 and 7^A, as heretofore explained. The construction, however, of 10 these two make-and-break devices is substantially identical, and they are only given different designations for convenience of explanation. Each make-and-break device is composed of a base 8, which is secured 15 to the base of the track rail in any suitable manner. Upon this base 8, is mounted a stationary housing member 9, coöperating with a vertically movable housing member 10, the member 10 being yieldingly supported, 20 whereby the contacts 14 and 15 are normally separated the one from the other, whereby the circuit is broken at the track except when the train is passing. The contact 14 is also spring-supported and rests upon the housing member 9, while the contact 15 is secured to the top of the housing member 10. The contacts are insulated from the respective housing members. The flange of any 25 wheel of the train will engage the housing member 10 and depress the latter sufficiently to bring the two contacts 14 and 15 into engagement. From the contact 15 of the make-and-break device 7, leads a wire or electrical conductor 16, to one terminal of the 30 coil of a solenoid F, having a core 17, connected by means of a spiral spring 18 and a cable, or other suitable flexible device 19, with the segment 20, of a semaphore arm 21, pivotally mounted, as shown at 22, upon a 35 post 23. From the opposite terminal of the coil of the solenoid F, leads a wire 24, to a magnet A, which is in the solenoid form and provided with a movable core 25, which is normally acted on by a leaf spring 26, 40 to hold the core at its limit of forward movement, the forward end of the core being beveled, as shown at 27, whereby it is adapted to be engaged by the correspondingly beveled extremity of a projection 28, formed on a 45 vertically-movable bar 29, mounted in guides 30, normally held at its upward limit of movement by a coil spring 31, one end of which rests upon the lower guide 30, while its upper end engages a stop collar 32, 50 formed on the bar. When at its upward limit of movement, the upper end of the bar presses against a spring contact 33, secured to a stationary member 34, whereby an electric circuit is closed through an electro-magnet E. From a terminal 35 of this magnet, 55 a wire 36 leads to the bar 29, while from the stationary member 34 of the spring contact 33, a wire 37 leads to one of the main feed wires 38; while from the opposite feed wire 60 39, leads a wire 40 to the opposite terminal 65 41, of the magnet E. Hence simultaneously with the passage of the current through the coils of the solenoid F, the movable core 17, of the solenoid, which previous to the energizing of the solenoid was in the position shown in Fig. 1, is drawn into the solenoid to the position shown in Fig. 2, whereby the semaphore arm 21, which was previously in the danger position, as shown in Fig. 1, is raised to the safe position or that shown in 70 Fig. 2, the solenoid core acting through the coil spring 18 and the cable 19. As soon as the core assumes the position shown in Fig. 2, its upper extremity which has a beveled head 42, engages the oppositely beveled ex- 75 tremity 43, of the armature bar 44 of the magnet E. The extremity 43 of the bar is hinged, as shown at 45, to allow it to move downwardly when engaged by the head 42 of the core, after which this extremity 43 is raised to the horizontal position by a leaf spring 46. In this event the short arm 47 of the armature bar forms a lock to hold 80 the solenoid core at the downward limit of movement. It will be understood that this bar 44 is pivotally mounted, the axis of the pivot coinciding with that of the hinge 45, whereby the bar unless supported, assumes the dotted line position in Fig. 1. However, when the semaphore arm 21, is in the danger 85 position as in Fig. 1, though the magnet E is deenergized, a wire 47 having a spring member 48, serves to support the armature bar in contact with the cores of the magnet E, or in such proximity thereto that as soon 90 as the last named magnet is energized, as heretofore explained, the bar 44 will be held tightly against the cores of the magnet, sufficient strength being exerted to maintain the bar in a position to lock the core 17, at 95 its downward limit of movement, (see Fig. 2,) in which position it will remain until the magnet E is deenergized, but this will not occur until the magnet B is energized and acts upon the bar 29 to pull the latter 100 downwardly into engagement with the core of the magnet, in which event the circuit of the magnet E will be broken. The opposite terminals of the magnet B are respectively 105 connected with wires 49 and 50. The wire 110 50 leads to a contact 51, which is adapted to be engaged by the upper extremity of a vertically movable bar 52, mounted in guides 53, normally held at its upward limit of movement by a coil spring 54, one extremity of 115 which rests upon the lower guide 53, while its upper extremity engages a stop collar 55. When the magnet D is energized, it acts 120 upon the bar 52, to draw the latter downwardly, whereby the said bar is separated 125 from the spring contact 51; thus breaking the circuit of the magnet B beyond or above the track make-and-break device 7^A.

When the magnet B is energized and draws the bar 29 downwardly to break the 130

circuit through the magnet E, the projection 28 acts to force the movable core 25 of the magnet A inwardly until the said projection passes below the said core, when the 5 spring 26 will force the core outwardly, causing the latter to assume a position above the projection 28, whereby the bar is locked in a position to break the circuit through the magnet E, in which event the 10 armature bar 44 is allowed to drop, releasing the core 17 of the solenoid F, and permitting the semaphore arm 21 to fall to the danger position. When the bar 52 is drawn downwardly by the energizing of the magnet 15 D, the said bar is locked in the said position by a core 56 of a magnet C, the said core being acted on by a spring 57, the core occupying a position above a projection 58, with which the bar 52 is provided. From 20 the lower contact 14 of the make-and-break device 7, leads a wire 16^A to the upper extremity of a bar 52, which is controlled by the magnet D' and is substantially of the same construction and function as the bar 25 52 controlled by the magnet D, and is therefore given the same reference character.

It will be understood that the individual members of the pairs of magnets A A', B B', C C', D D', E E' and the pair of solenoids F F' perform substantially identical functions, but are located on opposite sides of the track. Hence the apparatus coöperating with these corresponding magnets may be given the same reference characters. 35 Therefore when the magnet D' is energized, it acts upon the adjacent bar 52 to draw the latter downwardly, breaking the circuit of the magnet B' above or beyond the track make-and-break device 7, and the core 56 of 40 the magnet C' serves to lock the bar in the depressed position. When the magnet B' is energized, it serves to draw the adjacent bar 29, downwardly, breaking the circuit through the magnet E' and allowing the 45 magnet bar 44 of the last named magnet to drop to the dotted line position; (see Fig. 1) thus releasing the core 17, of the solenoid F' and, allowing the semaphore arm 21 to drop to the danger position, as shown in 50 Fig. 1. As soon as this occurs, however, the wire 47 containing the spring member 48, the said wire being connected with the armature bar 44 of the magnet E', draws the said bar toward the magnet and supports it 55 approximately in contact with the cores of the magnet and therefore within the influence of the power of the latter when energized, to hold the said bar in position to engage and lock the core 17 of the solenoid F' 60 at its limit of downward movement when the latter is energized.

From one terminal 41 of the magnet E', a wire 40 leads to the feed wire 39, while a wire 36 leading from the opposite terminal 65 of the magnet E' passes to the upper ex-

tremity of the bar 29 and thence through the spring contact 33, to a wire 37, which is in communication with the main feed wire 38.

Attention is called to the fact that the 70 contact 15 of the make-and-break device 7^A, is connected by means of a wire 16^B, with one terminal of the magnet F', whose opposite terminal is connected by means of a wire 24, with one terminal of the magnet A'; while the contact 14 of the make and break device 7^A is connected by means of a wire 16^C with the upper extremity of the bar 52 adjacent to the magnet D, the result being that whenever the contact 51 is in engagement with the bar 52 controlled by either magnet D or D', the magnet B or B', as the case may be, will be energized by the closing of the make-and-break device 7 or 7^A. 80

My present invention in common with that covered by my aforesaid application includes provision for automatically breaking the circuit above or beyond the track make-and-break device, of the magnet B or B', as the case may be, on the left hand side 90 of the track, one station in advance of the train, the term left hand side of the track meaning the side at the left considered with reference to the travel of the train in question, in order to neutralize the effect of closing the make-and-break device on the left hand side of the track as the train reaches any station. 95

It must be understood that any train traveling in a given direction only utilizes the make-and-break devices on the right hand side of the track for signaling purposes, the right hand make-and-break device at any station serving when closed, through the instrumentality of the various devices heretofore explained, to throw the semaphore arms to the danger position on the left hand side of the track in front and raise the semaphore arms to the safe or out of danger position at any predetermined distance in the rear. The make-and-break devices on the right-hand side of the track also serve to display a danger signal on the right hand side of the track at the station where the 110 make-and-break device is operated, and to change the signal from the danger to the safe position on the left hand side of the track at the said station. By virtue of this arrangement, the train always leaves danger signals behind it on the right hand side of the track and these danger signals are kept displayed until the train is a safe distance in advance, and they are successively changed to the safe position a predetermined 115 distance in the rear as the train passes the various signaling stations. The make-and-break devices on the right hand side of the track serve to change the danger signals to the safe position in the rear of the train and 120 125 130

on the right hand side of the track by closing the circuit through the solenoid F or F', as the case may be, and the magnet A or A', as the case may be, whereby the solenoid core 17, is drawn into the solenoid and the semaphore arm 21, raised to the safe position through the instrumentality of the cable 19, the core being locked in the said position by the armature bar 44 of the magnet E or E', the said magnet being energized by the closing of the circuit through the magnet E or E' by the releasing of the bar 29, which moves upwardly in response to the recoil of the spring 31, as soon as the core 25 of the magnet A is drawn inwardly sufficiently to disengage the projection 28.

When the semaphore arm is raised to the safe position (see Fig. 2) a spiral spring 60 is placed under tension and exerts a slight pull downward upon the said arm, the upper extremity of the spring being connected with the inner extremity of the arm by a flexible device 61, while the opposite extremity of the spring is secured to the post 23, as shown at 62. This construction insures the immediate return of the semaphore arm to the danger position as soon as the core 17 of the solenoid is released, by the breaking of the circuit of the magnet E or E'. Hence the energizing of the magnet A or A' and the solenoid F or F' serves to throw the semaphore arm to the safe position; the magnet B or B' when energized serves to break the circuit of the magnet E or E', whereby the semaphore arm drops to the danger position; the magnet D or D' when energized serves to break the circuit through the magnet B or B' at a point above or beyond the corresponding track make-and-break device; while the energizing of the magnet C or C' serves to release the bar 52 of the magnet D or D' and allows the same to move to a position to close the circuit through the magnet B or B'.

45 In describing the operation of the device from Fig. 1 of the diagrammatic view, the foregoing statements must be borne in mind.

In this description, it will be assumed that a train has just passed the make-and-break devices 7 and 7^A of the central station shown in the said view or that designated by the Roman characters V and VI. It must then be understood that the various magnets A, B, C, D and E and the solenoid F on one side of the track and A', B', C', D', E' and F' on the other side of the track are in the conditions illustrated in Figs. 1 and 2, and that the various mechanical devices disclosed in Figs. 1 and 2 are correspondingly located. In this diagrammatic view, it is assumed that the train is traveling in the direction of the arrow X, the train being represented by dotted lines indicating a pair of wheels connected by an axle and designated by the numeral 5, as

heretofore explained. Now as the train has just passed the make-and-break devices 7 and 7^A, the contacts of both these devices have been momentarily closed. When the contacts of the make-and-break device 7 are momentarily closed, the current may be said to pass from the contact 15 of the station V, VI, through the wire 16^A of the magnet B', from the latter through a conductor H, to the magnet C of the station III, IV, from the latter through the conductor J, to the solenoid F', thence through a conductor 24, to the magnet A' of the station I, II, thence through the conductor G to the main feed wire 37 of the magnet circuit, the other feed wire being designated by the numeral 40, as heretofore explained. The result of this travel of the electric current is to energize the magnet B' of the station V, VI, whereby a semaphore arm is dropped to the danger position on the right hand side of the track. The energizing of the magnet C at the station III, IV restores the continuity of the circuit of the magnet B at this station; the energizing of the solenoid F' at the station I, II throws the semaphore arm to the safe position, while the energizing of the magnet A' releases the bar 29 which under the influence of its spring closes the circuit of the magnet E' and holds the armature bar 44 in position to lock the solenoid core at its downward limit of movement, whereby the semaphore arm is maintained in the safe position.

Having now traced the path of the current in the rear of the train and its result when the make-and-break device 7 of the station is actuated to momentarily close its contacts, I will trace the path of the current forward of the train, resulting from the closing of the contacts of the same make-and-break device. In this event the current may be said to pass from the contact 15 of the make-and-break device 7 of the station V, VI, through the conductor 16 to the solenoid F, thence through a conductor 24 to the magnet A of the same station, thence from the last named magnet, through the conductor K of the magnet D of the station VII, VIII, from the last named magnet through a conductor L to the magnet B of the station IX, X, and thence from the last named magnet, through the conductor M, to the feed wire 40, of the magnet circuit. The result of this travel of the circuit is to energize the solenoid F, whereby the core 17, is drawn thereinto, and the semaphore arm raised to the safe position, the circuit of the magnet E being closed; whereby the core of the solenoid is locked in the position to hold the semaphore arm in the last named position at the station V, VI. The energizing of the magnet D at the station VII, VIII, actuates

the bar 52 of the magnet D to break the circuit of the magnet B at a point above or beyond the track make-and-break device 7^A; so that when the train reaches the station 5 VII, VIII, immediately in advance of its present position, the closing of the contacts of the make-and-break device 7^A at the last named station, will produce no result; while the energizing of the magnet B at the 10 station IX, X, results in breaking the circuit of the magnet E, whereby the core 17 of the solenoid F is released, allowing the semaphore arm 21 to drop to the danger position, two stations in advance of the train. 15 It will thus be seen that though both of the make-and-break devices 7 and 7^A at each station are actuated by the train to bring their contacts into engagement, the engagement of the contacts of the make-and-break device 7^A is devoid of results, since the circuit which otherwise would be closed through the magnets B and B', is broken at a point above or beyond the track, the broken condition of this particular circuit 20 being automatically accomplished by the train one station in advance of the latter, while the continuity of this particular circuit is restored automatically by the train one station in the rear thereof; thus leaving 25 the signaling apparatus intact and ready for use by a train traveling in the opposite direction, the last named train utilizing the make-and-break devices on the left hand side of a train moving in the direction of 30 arrow X, these devices being of course on the right hand side of a train traveling in the opposite direction.

Having thus described my invention, what I claim is:

1. A railway signaling apparatus, comprising signal stations, arranged along the track, each station including a semaphore arm located on each side of the track, electro-magnetic means for raising the semaphore arm, an electro-magnet for locking the semaphore arm in the raised position, the circuit of the said electro-magnet being normally closed, electro-magnetic means for breaking the said circuit, the said means having its circuit normally broken, circuit make and break devices arranged along the track on each side thereof at each station and adapted to be placed in the closed position by a passing train, and circuit connections between the track make and break devices at each station and the solenoid for raising the semaphore arm to the safe position and the electro-magnetic means for releasing the locking means at a station a predetermined distance in the rear of the train, substantially as described. 40
2. A railway signaling apparatus, comprising signal stations arranged along the track, each station including a semaphore arm, a solenoid, which when energized acts to raise the semaphore arm to the safe position, an electro-magnet, which when energized acts on the core of the solenoid to lock the semaphore arm in the safe position, the circuit of the electro-magnet being normally closed, an electro-magnet for breaking the said circuit, the said electro-magnet having its circuit normally open, means for locking the circuit of the first mentioned electro-magnet in the open position, when broken by the second mentioned electro-magnet, and electro-magnetic means for releasing the locking means, substantially as described. 45
3. A railway signaling apparatus, comprising signal stations arranged along the track, each station including a semaphore arm, a solenoid which when energized serves to raise the semaphore arm to the safe position, an electro-magnet for locking the semaphore arm in the safe position, the circuit of the electro-magnet being normally closed when in the locking position, electro-magnetic means for breaking the said circuit, the said electro-magnetic means having its circuit normally broken, means for locking the circuit of the electro-magnet in the open position, electro-magnetic means for releasing the said locking means, circuit make and break devices arranged along the track on each side thereof at each station and adapted to be placed in the closed position by a passing train, and circuit connections between the track make and break devices at each station and the solenoid for raising the semaphore arm to the safe position and the electro-magnetic means for releasing the locking means at a station a predetermined distance in the rear of the train, substantially as described. 50
4. A railway signaling apparatus, comprising signaling stations arranged along the track, each station including a semaphore arm, a solenoid connected with the semaphore arm and serving when energized to raise the semaphore arm from the danger to the safe position, an electro-magnet which when energized serves to lock the semaphore arm in the raised position, electro-magnetic means for breaking the circuit of the electro-magnet, means for locking the circuit of the electro-magnet in the open position, means for releasing the locking means, circuit make and break devices arranged along the track on each side thereof at each station and adapted to be placed in the closed position by a passing train, and circuit connections between the track make and break devices at each station and the solenoid for raising the semaphore arm to the safe position and the electro-magnetic means for releasing the locking means, substantially as described. 55

site direction, whereby the said electro-magnet is deenergized, allowing the semaphore arm to drop to the danger position, substantially as described.

2. A railway signaling apparatus, comprising signal stations arranged along the track, each station including a semaphore arm, a solenoid, which when energized acts to raise the semaphore arm to the safe position, an electro-magnet, which when energized acts on the core of the solenoid to lock the semaphore arm in the safe position, the circuit of the electro-magnet being normally closed, an electro-magnet for breaking the said circuit, the said electro-magnet having its circuit normally open, means for locking the circuit of the first mentioned electro-magnet in the open position, when broken by the second mentioned electro-magnet, and electro-magnetic means for releasing the locking means, substantially as described. 70

3. A railway signaling apparatus, comprising signal stations arranged along the track, each station including a semaphore arm, a solenoid which when energized serves to raise the semaphore arm to the safe position, an electro-magnet for locking the semaphore arm in the safe position, the circuit of the electro-magnet being normally closed when in the locking position, electro-magnetic means for breaking the said circuit, the said electro-magnetic means having its circuit normally broken, means for locking the circuit of the electro-magnet in the open position, electro-magnetic means for releasing the said locking means, circuit make and break devices arranged along the track on each side thereof at each station and adapted to be placed in the closed position by a passing train, and circuit connections between the track make and break devices at each station and the solenoid for raising the semaphore arm to the safe position and the electro-magnetic means for releasing the locking means at a station a predetermined distance in the rear of the train, substantially as described. 90

4. A railway signaling apparatus, comprising signaling stations arranged along the track, each station including a semaphore arm, a solenoid connected with the semaphore arm and serving when energized to raise the semaphore arm from the danger to the safe position, an electro-magnet which when energized serves to lock the semaphore arm in the raised position, electro-magnetic means for breaking the circuit of the electro-magnet, means for locking the circuit of the electro-magnet in the open position, means for releasing the locking means, circuit make and break devices arranged along the track on each side thereof at each station and adapted to be placed in the closed position by a passing train, and circuit connections between the track make and break devices at each station and the solenoid for raising the semaphore arm to the safe position and the electro-magnetic means for releasing the locking means, substantially as described. 115

device at each station and the solenoid for raising the semaphore arm and the lock-releasing electro-magnetic means at a station a predetermined distance from said 5 make and break device, whereby when any track make and break device is closed on one side of the track the solenoid and the lock-releasing electro-magnetic means are energized, the said circuit connections also 10 including the electro-magnetic means for breaking the circuit of the semaphore locking electro-magnet at a predetermined distance in the opposite direction, whereby the semaphore locking electro-magnet is de- 15 energized allowing the semaphore arm to drop to the danger position, substantially as described.

5. A railway signaling apparatus, comprising signaling stations arranged along 20 the track, each station including a mechanical signal, a solenoid for throwing the signal to the safe position, an electro-magnet for locking the signal in the safe position, electro-magnetic means for breaking the 25 circuit of the said electro-magnet for releasing the signal, a second electro-magnet for locking the circuit of the first named electro-magnet in the open position, circuit make and break devices arranged along the 30 track at each station and adapted to be placed in the closed position by a passing train, and circuit connections between each station and the solenoid and the second named elec- 35 tro-magnet for locking the circuit of the first named electro-magnet in the open position at a station a predetermined distance from said make and break device, whereby when the track make and break device is closed 40 at any station the solenoid and the second named electro-magnet are energized, the said circuit connections also including the electro-magnetic means for breaking the circuit of the said magnet for locking the signal 45 at a predetermined distance in the opposite direction, whereby the said magnet for locking the signal is deenergized, allowing the semaphore arm to drop to the danger position, substantially as described.

50 6. A railway signaling apparatus, comprising signal stations arranged along the track, each station having a signaling apparatus including a mechanical signal, a solenoid for throwing the mechanical signal 55 to the safe position, an electro-magnet for locking the mechanical signal in the safe position, the circuit of the electro-magnet being closed when the signal is in the safe position, means for breaking the circuit of the 60 electro-magnet, means for locking the

circuit of the electro-magnet in the open position, electro-magnetic means for releasing the locking means, circuit make and break devices arranged along the track at each station and adapted to be placed in the 65 closed position by a passing train, circuit connections between the track make and break device at each station and the solenoid and the electro-magnetic means for releasing the locking means, whereby when any track make and break device is closed the solenoid and the electro-magnet at a station a predetermined distance from the said make and break device are energized, the said circuit connections also including the means 75 for breaking the circuit of the electro-magnet at a predetermined distance in the opposite direction, whereby the electro-magnet is deenergized allowing the signal to drop to the danger position, substantially as de- 80 scribed.

7. A railway signaling apparatus, comprising signaling stations arranged along the track, each station including a mechanical signal, a solenoid for throwing the mechanical 85 signal to the safe position, an electro-magnet for locking the signal in the safe position, an electro-magnet for breaking the circuit of the first named electro-magnet, means for locking the circuit in the broken 90 circuit position, electro-magnetic means for releasing the locking means, circuit make and break devices arranged along the track at each station and adapted to be placed in the closed position by a passing train, and circuit connections between the track make 95 and break device at each station and the solenoid for throwing the signal to the safe position and the electro-magnetic means for releasing the locking means at a station at 100 a predetermined distance from said make and break device, whereby when any track circuit make and break device is closed on one side of the track, the solenoid and the lock-releasing device are energized, the said 105 circuit connections also including the electro-magnetic means for breaking the circuit of the first mentioned electro-magnet at a predetermined distance in the opposite direction, whereby the said electro-magnet is deenergized, allowing the signal to drop to the danger position, substantially as de- 110 scribed.

In testimony whereof I affix my signature in presence of two witnesses.

WILLIAM J. COOK.
